(57) **CLAIM**

The ornamental design for a handle for hair styling tool, as shown and described.

DESCRIPTION

FIG. 1 is a front perspective view of a handle for hair styling tool, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof, shown in a first environment of use;

FIG. 10 is a perspective view thereof, shown in a second environment of use;

FIG. 11 is a perspective view thereof, shown in a third environment of use;

FIG. 12 is a perspective view thereof, shown in a fourth environment of use;

FIG. 13 is a perspective view thereof, shown in a fifth environment of use;

FIG. 14 is a perspective view thereof, shown in a sixth environment of use;

FIG. 15 is an enlarged view of portion “15” shown in FIG. 1; and,

FIG. 16 is an enlarged view of portion “16” shown in FIG. 2.

In the drawings, the evenly-spaced broken lines illustrate portions of the article and form no part of the claimed design. In FIGS. 9-14 additional broken lines illustrating attachment tools illustrate environmental subject matter and

(Continued)

form no part of the claimed design. The dash-dot-dash broken lines illustrate enlarged view indicators and form no part of the claimed design.

1 Claim, 16 Drawing Sheets
